UNITED STATES PATENT OFFICE.

WILLIAM B. FAGEOL, OF OAKLAND, CALIFORNIA.

REPEATING ATTACHMENT FOR PHONOGRAHS.

Application filed January 21, 1927. Serial No. 162,494.

This invention relates to mechanisms used in phonographs for automatically repeating the playing of a record.

It is the chief object of the invention to devise a mechanism of this character which will be extremely simple in construction, will be entirely reliable in operation, and which can be manufactured economically.

The nature of the invention will be readily understood from the following description when read in connection with the accompanying drawings, and the novel features will be particularly pointed out in the appended claims.

In the drawings,

Figure 1 is a plan view showing a mechanism embodying this invention attached to the tone arm of a phonograph;

Fig. 2 is a side elevation of the mechanism shown in Fig. 1;

Fig. 3 is a plan view showing a mechanism embodying this invention applied to a phonograph of a different type from that shown in Figs. 1 and 2;

Fig. 4 is a cross-sectional view substantially on the line 4—4, Fig. 3;

Fig. 5 is a cross-sectional view substantially on the line 5—5, Fig. 3; and

Figs. 6 and 7 are plan and side views, respectively, showing still another embodiment of the invention.

Referring first to Figs. 1 and 2, the construction there shown comprises a tone arm 2 mounted for swinging movement about a vertical pivot 3 and carrying a goose neck 4 which forms, in effect, a continuation of the tone arm 2. The goose neck carries a reproducer or sound box 5, this reproducer having a holder for the needle or stylus 6 which runs in the grooves of the disk record 7. This record is supported on a revolving table 8 which is mounted on the upper end of a spindle or shaft 9, and the tip 10 of this spindle projects through the table and record and serves as a centering pin for the records. The pivotal support of the tone arm permits it to swing in a horizontal plane as the reproducer 5 travels laterally across the record 7, and the goose neck is mounted for pivotal movement about a horizontal axis transverse to the axis of the tone arm, so that the reproducer 5 can be swung upwardly out of playing position, with the needle off the record, or downwardly into said position again.

The parts so far described are those of a well known make of phonograph.

The mechanism embodying this invention as illustrated in Figs. 1 and 2, comprises a lever 12 fulcrumed at 13 on a clamp 14 which is removably secured to the tone arm 2. This lever includes a weighted rearward end 15 and a curved forward arm 16 which projects under the part of the goose neck 4 immediately adjacent to the reproducer. A screw 17 is threaded vertically through the end of the arm 16 and is adapted to engage the goose neck. The operating element for this mechanism consists of a cam 18 rotatably mounted on a horizontal shaft 19 which projects laterally from the lever 12. Preferably the edge of the cam is covered with rubber, leather, or some equivalent material.

It will be observed that the cam 18 is offset laterally from the tone arm in a direction inwardly with reference to the record 7, so that when the playing of the record is begun the cam 18 will be positioned over the central portion of the record 7. At this time the cam is held out of engagement with the record by the weighted end 15 of the lever 12. Also, the "low point" *a* of the cam disk, that is, the point on the surface nearest to the axis, is lowermost and close to the record, the cam being prevented from rotating under the influence of gravity by a stop pin 20, Fig. 1, which projects from the hub of the cam 18 and at this time engages another stop 21 projecting from the arm 12 at the lower side of the shaft 19.

For the purpose of moving the cam 18 into contact with the record when the playing of the record has been substantially completed, a stop screw 22 is arranged to engage the weighted end 15 of the lever 12, this screw being threaded through an upwardly projecting arm of a stationary bracket 23 which is screwed to the top of the phonograph cabinet. When the screw engages the curved lower side of the lever arm 15 as the tone arm and lever are being carried inwardly of the record 7, the screw swings the right-hand end of the lever 12 downwardly, thus bringing the edge of the cam 18 into contact with the record 7. The movement of the record revolves the cam 18 in a clockwise direction, Fig. 2, and, due to the eccentric shape of the cam, its rotative movement results in lifting the right-hand end of the lever 12, thus bringing the

screw 17 into contact with the goose neck 4 and lifting the reproducer out of playing position, or, in other words, lifting the needle 6 out of contact with the record. The 5 rotative movement so imparted to the cam 18 is limited by the stop pins 20—21, previously referred to, and the record 7 immediately begins to transfer the cam disk and the tone arm, swinging the arm outwardly 10 toward its initial position. This transferring movement continues until the cam arrives at a point on the other side of the central part of the record where the direction of travel of the record is such that it 15 rotates the cam in a direction opposite to its previous direction of rotation. This reverse rotation results in lowering the reproducer 5 into playing position again with the needle 6 in contact with the grooved 20 portion of the record.

In order to limit the outward or resetting movement of the tone arm, the bracket 23 is provided with a second upwardly extending arm through which a stop screw 25 is 25 threaded, this screw being positioned to engage a lug 26, Fig. 2, which projects downwardly from the clamp 14. The adjustability of the screw permits the setting of it for different sizes of records and also to 30 accommodate variations in the distance inwardly from the edge at which the record grooves begin on different records of the same size.

It will be observed that due to the offset 35 arrangement of the cam with reference to the tone arm, the cam is located, when the playing of a record is begun, at a point between the sound box and the line $b-b$ connecting the axes of the pivots 3 and 10. 40 During the playing of the record the cam moves laterally across said line $b-b$ and away from the central part of the record. Consequently, when the cam is lowered into contact with the record 7 it strikes a part 45 of the record which is moving at a relatively high speed. The subsequent resetting or transferring movement of the cam and the tone arm results in moving the cam into contact with a part of the record much closer 50 to the center pin 10, so that when the reverse rotation of the cam occurs, the disk then is driven by a part of the record which moves at a comparatively slow speed. This arrangement is of advantage in lowering the 55 reproducer gradually into its playing position and bringing the needle 6 slowly down into contact with the record grooves.

Figs. 3, 4 and 5 show a slightly different attachment embodying this invention and 60 applied to that style of phonograph in which the tone arm is not equipped with a pivoted goose neck but is itself mounted for pivotal movement both vertically and horizontally. In this embodiment of the invention the 65 parts similar to those shown in Figs. 1 and

2 are designated by corresponding but primed numerals.

The tone arm clamp 14', lever 12', and stop screws 22' and 25' are arranged and operate substantially as in the arrangement 70 previously described. In this construction, however, the cam 18' is mounted to rotate around a shaft 27 which performs the functions of both the shaft 19 and lever extension 16 of the mechanism above described. 75 This shaft carries a roll 28 which is positioned under the part of the tone arm adjacent to the reproducer 5', and lifts the reproducer when the playing of a record is finished. The tone arm is supported in a 80 bracket or fixture 29 so that it can swing horizontally about a vertical axis 3', and can also pivot vertically. The operation of this mechanism is essentially like that of the mechanism shown in Figs. 1 and 2. 85

A further modification is shown in Figs. 6 and 7. In this arrangement the tone arm 2, goose neck 4 and reproducer 5 are constructed substantially as shown in Fig. 1. The cam 30 in this instance is made of heavy wire covered with rubber and it is mounted to rotate on a shaft 31 which is supported in a bearing that is either made integral with, or is secured fast to, the goose neck extension 4 of the tone arm. The cam is held in an inoperative position by cooperating stops 32—33, Fig. 6, as the reproducer travels laterally across the record, but as the playing of the record nears completion, an extension 34 of the cam strikes the inclined portion 35 of a stationary arm which overlies the record. Further lateral inward movement of the tone arm then results in swinging the disk downwardly into contact with the record 7, thus causing the record to 100 rotate the disk in a direction to raise the reproducer out of playing position. The reproducer and cam are then transferred by the record to their initial positions where the direction of rotation of the record is 105 such that it reverses the movement of the cam 30, causing it to lower the reproducer again into playing position. This transferring movement is limited by an adjustable screw 36 which corresponds in function 110 to the screw 25 of the construction shown in Figs. 1 and 2. 115

It will now be evident that this invention provides an extremely simple mechanism for causing a phonograph to repeat the playing 120 of a record automatically as many times as desired. The mechanism can be manufactured very economically, it is easily attached to a machine, and it requires the making of only very simple adjustments to accommodate different records. It is extremely reliable in operation.

While I have herein shown and described the best embodiments of the invention that I have so far devised, it will be evident that 125

the invention may be embodied in other forms without departing from the spirit or scope thereof.

Having thus described my invention, what I desire to claim as new is:

1. A repeating mechanism for disk phonographs comprising, in combination, a device arranged to be operated by the phonograph record to raise the reproducer out of playing position and to lower it again into said position, supporting means for said device connected with the tone arm and operative to cause the tone arm to move said device from one side of the central portion of the record to the other, means for holding said device out of contact with the record during the playing of the record, and means for lowering the device into contact with the record when the playing of the record has been substantially completed.

2. In a repeating attachment for phonographs, a mechanism for raising the reproducer out of playing position and returning it again to said position, comprising a cam, means for supporting said cam for movement laterally across the record with the tone arm from a point on the record operative to rotate the cam in one direction to another point operative to rotate it in the opposite direction, and means for controlling the engagement of said cam with the record.

3. In a repeating attachment for phonographs, a mechanism for raising the reproducer out of playing position and returning it again to said position, comprising a cam, means for supporting said cam for movement laterally across the record with the tone arm from a point on the record operative to rotate the cam in one direction to another point operative to rotate it in the opposite direction, means for moving said cam into operative contact with the record at substantially the completion of the playing of the record, whereby the cam is operated by the record to raise said reproducer, transfer it to its initial position, and lower the reproducer again, and means for limiting said transferring movement of the reproducer.

4. In a repeating attachment for phonographs, a mechanism for raising the reproducer out of playing position and returning it again to said position, comprising a cam, means for supporting said cam for movement laterally across the record with the tone arm from a high speed point on the record operative to rotate the cam in one direction to a low speed point operative to rotate the cam in the opposite direction, means for holding said cam in an inoperative position during the playing of the record, and means for moving said cam into operative contact with the record substantially at the completion of the playing of the record, said cam being arranged to be

operated by the record to lift the reproducer out of playing position, to be carried by the record to substantially its initial position, and then to lower said reproducer into playing position again.

5. In a repeating mechanism for disk phonographs, the combination with a tone arm and a reproducer connected thereto, of a cam, means supporting said cam for movement across the record in unison with the tone arm, said cam being arranged to be rotated in opposite directions by contact with the record at different points and operative when rotated in one direction to raise the reproducer out of playing position, and when rotated in the opposite direction to lower said reproducer into playing position again, means for holding said cam in an inoperative position during the playing of the record, means for moving said cam into operative contact with the record approximately when the playing of a record has been completed whereby the cam will be rotated to raise the reproducer, transfer it to its initial position and lower the reproducer again, and adjustable means for limiting said transferring movement of the reproducer.

6. In a disk phonograph, the combination with a reproducer and a tone arm pivoted for movement therewith across a record, of a rotatable device for raising and lowering said reproducer, means for connecting said device with said tone arm for movement therewith across the record from one side to the other of a line connecting the axis of rotation of the record with the pivotal axis of said tone arm, and means for moving said device into contact with the record when the playing of the record has been substantially completed, said device being operable upon its rotation by said record in one direction to raise said reproducer, then to move in the same general direction as the record to transfer the reproducer to its initial position, and then to be rotated by said record in a reverse direction to lower the reproducer into playing position.

7. In a disk phonograph, the combination with a reproducer and a tone arm pivoted for movement therewith across a record, a lever carried by said tone arm, a cam carried by said lever and mounted for limited rotation on a substantially horizontal axis, said cam being offset laterally from the tone arm but movable laterally therewith, a stop arranged to act on said lever when the playing of a record has been substantially completed to move said cam into engagement with the record, whereby it is rotated by its contact with the record to raise said reproducer out of playing position, is then transferred by the record, with the reproducer, to approximately its initial position, and then is rotated by the record in a reverse direc-

tion to lower the reproducer into playing position, and means for limiting the transferring movement of the reproducer.

8. In a repeating mechanism for disk phonographs, the combination with a tone arm, of a lever carried by said tone arm, a cam mounted on said lever for limited rotation and offset from the tone arm so that when the playing of a record is begun the cam is positioned between the center of the record and the tone arm and when the playing of the record is completed the cam will be on the opposite side of said center, said lever having a part positioned to lift the reproducer, and means for operating said lever to move said cam into contact with the record substantially upon completion of the playing of the record.

9. A repeating attachment for disk phonographs comprising, in combination, a clamp adapted for attachment to the tone arm of the phonograph, a lever fulcrumed on said clamp, a cam carried by said lever, said lever having an extension to lift the reproducer, a device for acting on said lever to swing it on its fulcrum at substantially the completion of the playing of the record, and a stop for limiting the swinging movement of the tone arm.

10. In a repeating mechanism for disk phonographs, the combination with a tone arm and a reproducer connected thereto, of a cam mounted on the tone arm for lateral movement across the record in unison with the tone arm but for rotative movement rela-

tively to said tone arm, means for holding said cam in an inoperative position during the playing of a record, means for moving said cam into contact with the record approximately when the playing of the record has been completed, whereby the cam will be rotated to raise the reproducer, transfer it to its initial position, and then rotated in the opposite direction by the record to lower the reproducer again, and means for limiting said transferring movement of the reproducer.

11. In a repeating mechanism for disk phonographs, the combination with a tone arm and a reproducer connected thereto, of a cam mounted on the tone arm for lateral movement across the record in unison with the tone arm but for rotative movement relatively to said tone arm, said cam adapted to be rotated in opposite directions by contact with the record at different points and being operative when rotated in one direction to raise the reproducer out of playing position and when rotated in the opposite direction to lower said reproducer again into playing position, stop means for holding said cam in an inoperative position during the playing of a record, said cam having an extension projecting therefrom, and an arm arranged to engage said extension substantially at the completion of the playing of a record to rotate said cam far enough to bring it into operative contact with the record.

WILLIAM B. FAGEOL.
